UNITED STATES PATENT OFFICE

RUSSELL W. AYRES, OF SCHENECTADY, NEW YORK, ASSIGNOR TO GENERAL ELECTRIC COMPANY, A CORPORATION OF NEW YORK

CONDENSER FOR REFRIGERATING MACHINES

Application filed March 1, 1932. Serial No. 596,062.

My invention relates to air cooled condensers, for refrigerating machines, of the type having a passageway through which the refrigerant flows, the refrigerant being cooled and condensed by the circulation of air, which is induced either by forced or natural draft.

The object of my invention is to provide an improved condenser of this type having a fluid passageway formed between sheets of metal, and to provide a fabricated construction which is simple and inexpensive to manufacture.

Further objects and advantages of my invention will become apparent as the following description proceeds, and the features of novelty which characterize my invention will be pointed out with particularity in the claims annexed to and forming a part of this specification.

20 In the drawings, Fig. 1 is a front view, partly in section, of my improved condenser arranged about a casing of a refrigerating machine; Fig. 2 is a plan view of the construction shown in Fig. 1; Figs. 3 and 4 are 25 side elevations of corrugated sheets of metal of the forms which I employ in forming the condenser shown in Figs. 1 and 2; and Fig. 5 is a fragmentary perspective view of the sheets shown in Figs. 3 and 4 after 30 they have been united at their top and bottom edges and bent into cylindrical form.

In Figs. 1 and 2 of the drawings, I have shown my invention in connection with a compression refrigerating machine of the 35 general construction described and claimed in United States Letters Patent No. 1,736,635, granted November 19, 1929, on the application of Christian Steenstrup, to the assignee of the present invention. In the construction 40 shown in the accompanying drawings, this machine comprises a motor and compressor unit arranged in a refrigerant containing casing 1 which is mounted on a base 2 adapted to be removably supported in an 45 opening in a refrigerator cabinet. A plurality of fins 3 are attached to the casing 1 for effectively dissipating the heat from the motor and compressor within the casing 1. During operation of the machine the refrigerant 50 gas is discharged from the compressor

into the casing 1, and flows through a connection 4 into an air cooled condenser 5 embodying my invention. The refrigerant is 55 condensed in the condenser 5 and flows therefrom, through a connection 6 and a flow controlling device 7, which maintains the desired difference in pressure between the condenser and the evaporator during operation of the machine, into an evaporator 8 secured to the base 2, and arranged within 60 the refrigerator cabinet. The vaporized refrigerant is withdrawn through pipe 9 from the evaporator 8 by the compressor, in which it is compressed again and the refrigerating cycle repeated. The motor in the casing 1 65 is controlled in response to the temperature of the evaporator 8 by a thermostatic device 11. A valved connection 10 communicates directly with the condenser 5 through the connection 6, between the flow controlling device 7 and the condenser, for charging the machine, or purging the machine of any non-condensable gas that may accumulate in the condenser.

In accordance with my invention the condenser 5 is fabricated of sheet metal, and made annular in form to minimize the number of welds or joints required to withstand the pressure to which the condenser is subjected.

I make the condenser 5 by forming the sheets of metal 12 and 13, as shown in Figs. 3 and 4, with longitudinal grooves 17 and 18, which terminate at the ends of the sheets, and at the same time forming grooves in the sheets, which connect the longitudinal 75 grooves in pairs at opposite ends to form continuous zig-zag grooves extending from the top to the bottom of the sheets. Inlet and outlet openings 23 and 24 are punched in the sheet 13 at the opposite ends of the zig-zag 80 groove therein. After the sheets 12 and 13 are formed in this manner, I place them together, so that the zig-zag grooves in the sheets are aligned with each other to form the continuous passageway 16, unite the edges 85 at 14 by welding, and fold over the edges of the sheet 12, as indicated at 14 in Figs. 1 and 5, to reinforce the joint. After the sheets are united at their edges and the edges of the sheet 12 are folded over, I bend the entire 90 95 100

construction into cylindrical form and weld the end edges 25 of the sheets together. I prefer not to weld these end edges of the sheets together until after the sheets are bent into cylindrical form, so that the inner sheet will be free to creep on the outer sheet in bending and thereby avoid buckling of the inner sheet, which might weaken the construction. I overlap and weld the opposite ends of the sheets together to form an annular body, as indicated at 15 in Fig. 2. I weld the arms of the U-shaped plates 19 about the upper portion of the sheet 13 at 20, and support the entire structure about the casing 1 in spaced relation to the base 2 of the refrigerating machine by riveting the inner ends of the plates 19 to the outer ends of the upper portion of the fins at 21, as shown in Figs. 1 and 2, heat insulating bushings 19' being arranged on the rivets between the plates 19 and fins. I then secure the connection 4 between the inlet opening 23 and the casing 1, and the upper end of the pipe 6 in the outlet opening 24 to connect the passageway 16 with the flow controlling device 7 and the evaporator 8.

In this construction it is not necessary to weld the sheets 12 and 13 together between the corrugations in the sheets, because bending the sheets into cylindrical form stretches the outer sheet 12 about the sheet 13 in close contact therewith and confines the flow of refrigerant to the zig-zag passage 16 formed by the grooves in the sheets. Moreover, the grooves in the sheets 12 and 13 reinforce the construction, and prevent the separation of the sheets by the pressure of the refrigerant gas.

It will thus be seen that I have provided an improved condenser, in which the sheets of metal of cylindrical form are utilized as an air flue, and have a large external surface presented to the surrounding air for effectively cooling and condensing the refrigerant flowing through the zig-zag passageway formed therein. Moreover, a simple fabricated construction is obtained in which the inner cylindrical sheet is retained in close contact with the outer sheet, so that welding of the sheets between the grooves forming the refrigerant passageway is unnecessary. This produces an inexpensive and easily manufactured construction.

Although I have illustrated and described a particular embodiment of my invention, I do not desire to be limited to the particular arrangement set forth, and I intend in the following claims to cover all modifications which do not depart from the spirit and scope of my invention.

What I claim as new and desire to secure by Letters Patent of the United States is:

1. An air-cooled condenser for refrigerating machines including a body having contacting metallic sheets joined together at the

ends thereof to form an annulus, one of said sheets having a continuous zig-zag groove cooperating with the other of said sheets to form a passageway extending from one side of said joint about said body and between 70 said sheets to the other side of said joint.

2. An air cooled condenser including a casting, an annular body arranged about said casting, said annular body comprising contacting metallic sheets having the edges thereof 75 united and the opposite ends thereof fastened together, one of said sheets having longitudinal grooves terminating at the ends thereof and connected in pairs at opposite ends so as to form a continuous zig-zag passageway extending within said body between said sheets.

In witness whereof, I have hereunto set my hand.

RUSSELL W. AYRES.
